Primary Examiner — Keli L Hill(74) *Attorney, Agent, or Firm* — Lewis Roca Rothgerber Christie LLP(57) **CLAIM**

The ornamental design for a bottle sleeve, as shown and described.

DESCRIPTION

FIG. 1 is a perspective view of a bottle sleeve showing my new design;

FIG. 2 is a front view thereof with the back view, left view, and right view being mirror images of the front view;

FIG. 3 is a top view thereof;

FIG. 4 is a bottom view thereof; and,

FIG. 5 is a perspective view of the bottle sleeve as shown disposed on a bottle with a cap and handle.

The broken line showing of the bottle, cap, and handle is for the purpose of illustrating the environment and boundary related to the claimed design and forms no part of the claimed design.
